SIRUP PUMP

Myron E. Steczynski, Walter W. Biederstadt, and
Earl V. Rupp, Chicago, Ill., assignors to The
Bastian-Blessing Company, Chicago, Ill., a cor-
poration of Illinois

Application April 28, 1949, Serial No. 90,209

19 Claims. (Cl. 222—309)

1 This invention relates generally to pumps and more particularly to an improved syrup pump for use in soda fountains.

In soda fountains the various flavored syrups used in making soft drinks, sodas and sundaes are usually stored in ceramic receptacles or jars which are supported in the top of the fountain in a row, their bottoms dipping into a refrigerated space within the fountain so that the syrup is kept cool. To dispense the syrups each jar is provided with a hand operated pump for transferring a measured amount of syrup from the jar to the container in which the beverage is being mixed or to the ice cream dish.

The syrups used are, for the most part, concentrated sugar solutions containing flavors and are susceptible to spoiling, fermenting, etc. due to the action of bacteria, molds and yeasts. Furthermore, many syrups are almost ideal media for the growth of germs and bacteria. The refrigeration of the syrup jars helps to prevent spoiling and organism growth, but it is also necessary to completely and thoroughly wash both the jars and pumps at regular intervals if satisfactory sanitation is to be achieved and also to remove sugar deposits which interfere with the operation.

Accordingly, one important object of this invention is to provide a pump which may be thoroughly washed with a minimum of effort on the part of the fountain attendant, the pump being capable of being disassembled without tools into its component parts, and the individual parts being easy to clean having no inaccessible cavities or hollows.

Another object is to provide a positive action pump which delivers a measured volume of syrup each time a handle is pressed, provision being made for adjusting the volume delivered per stroke as desired either to vary the composition of the drinks produced thereby or to compensate for differences in concentration of the syrups dispensed.

A further object is to provide an improved volume adjustment arrangement whereby the volume may be varied without altering the normal position of the operating handles thereby improving the appearance of the fountain, and the attendant can see at a glance when a handle has come to rest and is ready for a second actuation.

A further object is to provide a pump which will deliver the exact volume desired without dripping even though viscous syrups are being dispensed, the syrup being positively sucked away from the discharge opening as the handle returns

to its starting position, and provision being made to prevent any syrup adhering in the neighborhood of the discharge opening from dripping therefrom.

Other and additional objects and advantages of this invention will present themselves to those familiar with the art on reading the following specification in conjunction with the drawings and the appended claims.

2 In the drawings:

Fig. 1 is a vertical section of a preferred embodiment of the pump of this invention mounted in a syrup jar which would be tilted as indicated by the syrup level;

Fig. 2 is a side view, partially in section, of another embodiment especially adapted for dispensing more viscous syrups;

Fig. 3 is an enlarged section showing the positions of the pump elements of preferred embodiment during the pumping stroke;

Fig. 4 is an enlarged section showing the positions of the pump elements during the return stroke;

Fig. 5 is a horizontal section taken on line 5—5 of Fig. 3;

Fig. 6 is an enlarged view showing the bayonet lock arrangement by which the pump cylinder is removably supported on a head plate; and

Fig. 7 is a section taken on line 7—7 of Fig. 1. The preferred embodiment of the pump 10 is shown in Fig. 1 as it appears when mounted on a jar 11 containing syrup 12. For purposes of convenience, the pump 10 and jar 11 are shown in the vertical position in the drawings. Actually, however, the jar 11 is mounted on an angle to the vertical as indicated by the inclination of the liquid surface within the jar 11. The pump 10 will operate either in the vertical position or at an angle, but it has been especially designed for operation at a slight angle since the jars in most fountains are inclined so as to lean toward the work side of the fountain.

The elements of the pump 10 are supported by a plate 13 which, in addition to serving as a mounting plate, also is a removable cover for the jar 11. The plate 13 is preferably oval in shape and is provided with a flange 14 which fits over a projecting ring 15 on the top of the jar 11. The pump 10 comprises a discharge tube 16 preferably brazed to the plate 13 as indicated at 17, a cup assembly 18 and a handle assembly 19. The portion of the tube 16 below the plate 13 is straight while that portion above the plate is curved, making an angle of approximately 45° with the straight portion. The tube 16 also

serves as the sole support for the cup assembly 18 in the preferred embodiment.

This assembly 18 comprises a circular head or plate 20 which is brazed to the tube 16. The periphery of the plate 20 is provided with three projections 21, as shown in Figs. 5 and 6, which serve to support the cylindrical cup 22. The cup 22 is provided with a bayonet slot 23 corresponding to each of the projections 21 (Figs. 5 and 6) and is attached to the plate by slipping the projections 21 into the slots 23 and turning the cup a few degrees to lock same in position.

The inside wall of the cup 22 is cylindrical and smooth, for it cooperates with the movable piston 25 which is attached to the end of a rod 26 extending upwardly to the handle 27. The rod passes through an opening 28 in the plate 20 and, when the handle 27 is moved, its motion is transmitted through the rod to the piston 25 as shown in Figs. 1, 3 and 4.

The discharge tube 16 extends through the plate 20 to a position near the bottom of the cup 22, an opening 30 being provided in the piston 25 for the tube 16. The lower end of this tube receives a check valve assembly 32 containing a ball check 33. The assembly 32 is supported in the tube 16 solely by friction and the slight outward pressure of the ball retaining prongs 34 against the wall of the tube 16. Thus, assembly 32 may be readily removed from the end of the tube 16 simply by grasping its lower end between the fingers and pulling downwardly thereon. The bottom portion 35 of the assembly 32 is disc-like in shape and preferably integrally formed with the ball retaining prongs 34. A round port 36 is provided at the center thereof, and the ball 33 seals this port when in the position shown in Fig. 4. The upper ends of the ball retaining prongs 34 are turned in so as to provide sufficient clearance for the free flow of liquid and yet retain the ball 33. The prongs 34 are made of sufficient length to permit cleaning between the base and the inside surface of the port 36.

Because the check valve assembly 32 is removable, it is extremely simple to clean. After removal the attendant submerges the assembly in water and passes a brush back and forth between the prongs 34 to clean them. Next, he reverses the assembly 32, permitting the ball 33 to move to the opposite end and passes the brush through the opening 36 and between the prongs 34 to thoroughly clean the port 37.

To facilitate cleaning it is preferred that the valve 32 be made in one piece with generous fillets between the ball retaining prongs 34 and the bottom portion 35 eliminating sharp interior corners. The assembly 32 is preferably machined from rod stock, the upper ends of the prongs 34 being left straight until the ball 33 is dropped into place. After this the ends of the prongs 34 are bent inwardly to retain the ball 33 and the prongs proper 34 are sprung slightly outwardly so as to normally diverge and exert a pressure against the sides of the tube 16 when installed therein.

The bottom of the cup 22 is provided with a relatively large inlet port 37 which permits syrup to enter during the return stroke of the piston 25 without developing any substantial back pressure upon the valve 33 that might dislodge the assembly 32. To seal this port during the pumping stroke, a check valve 38 is provided. The valve 38 is supported in a guide or retainer 40 which rests on the bottom of the cup 22. The guide 40 is preferably made with its ends shaped to

receive a spring and with its center portion raised to provide the necessary lift of the valve. This retainer can be made of a flat strip of metal formed to provide the desired contour indicated in Figs. 3 and 4. The valve member 38 comprises a short stem 41 having a flat disc 42 brazed thereto. The stem 41 rides in an opening 43 in the guide 40 and thus retains the valve 38 in place, downward movement being limited by the bottom of the cup 22.

A helical return spring 44 is disposed within the cup 22 close to the cylindrical side thereof, and bears against both the piston 25 and the top of the valve guide 40, serving the dual function of providing force for the return stroke of the piston 25 and also holding the valve guide 40 in position against the bottom of the cup 22.

The upper end of the rod 26 is threaded as indicated at 45 so that the stroke of the piston 25 may be varied to change the amount of syrup delivered. Upward movement of the piston 25 is limited by the plate 20. Downward movement, however, is limited by a stop member 46 and a sleeve 47 which is supported on the mounting plate 13. When the handle 27 is pushed all the way down, a shoulder 48 on the bottom of the member 46 comes to rest against the top of the sleeve 47, thereby preventing further downward travel of the piston 25 and limiting the stroke thereof. A threaded collar 50 is provided which centers the shaft 26 in the sleeve 47 and also serves as a lock nut for the member 46.

To adjust the height of the shoulder 48 with respect to the rod 26 the collar 50 is screwed downwardly to free the member 46 which is then screwed to the desired vertical position corresponding to the volume of syrup to be pumped. The collar 50 is then screwed up tight against the stop 48 to lock it in that position.

The handle 27 may be integral with the member 48 but is preferably separate therefrom being threaded internally and screwed onto the shaft 26. Thus, the vertical position of the handle 27 is independent of the adjustment of the stop 46. The particular advantage of this feature is apparent when it is remembered that the jars 11 in soda fountains are mounted in horizontal rows side by side. If the tops of the handles are not in a line the appearance is spoiled and the attendant's job is made harder, for he is never sure that a handle is not stuck part way down or that he has pumped a full measure.

The handle assembly 19a of the modified embodiment shown in Fig. 2 differs from that described above in that a lever 52 is provided in order to increase the force which may be applied on the rod 26, the pump 10a being intended primarily for more viscous syrups. Otherwise, the two embodiments are substantially the same.

60 The lever 52 is pivoted about a bolt 53 supported on an arm 54 formed integrally with the sleeve 47a. A stop member 46a and a collar 50a are provided and function in the same manner as their counterparts in the preferred embodiment to control the length of the pumping stroke and hence the volume of liquid dispensed with each stroke, and to center the rod 26a.

Above the stop member 46a an element 55 is threadably attached to the top of the rod 26a and is adjustable vertically with respect thereto. The top of this element is flat and cooperates with a roller 56 journalled on the lever 52, the roller 56 bearing against the flat surface to exert a downward force on the rod 26a as the

handle 27a is moved. Furthermore, this adjustment 55 serves to position the lever 52 in the same position regardless of stroke adjustment. As the stroke is reduced the adjustment 55 is withdrawn to retain the position of the lever.

The force which is developed on the rod 26a by this arrangement is several times that developed in the previously described embodiment due to both the multiplying effect of the lever 52 and the cam action between the roller and the top of the element 50. Because of the increased force involved it is desirable to provide additional support for the cup assembly 18. This is accomplished by a rod 59 which extends downwardly from the cover plate 13 to the plate 21 which forms the top of the cup assembly 18. This rod is disposed on the opposite side of the actuator rod 26a from the discharge pipe 16 and is preferably brazed to both of the plates 13 and 21. This reinforcing rod is also used in the embodiment of Fig. 1 to provide additional reinforcement.

The discharge tubes 16 in both embodiments are identical and are especially constructed so as not to drip and to be easy to clean. It will be noted that the tube 16 consists of two straight portions connected by a rather sharply curved portion. This permits a brush to be inserted from either end to clean the whole tube 16. The arrangement whereby the check valve assembly 32 may be pulled out of the lower end of tube 16 has already been described. The upper end of the tube 16 is also constructed so that it can be completely disassembled for cleaning. This is accomplished by fashioning a discharge outlet nozzle and opening 57 on the side of the tube 16 and an external thread 58 on the end for receiving a cap 60. This cap serves to hold a removable plug 61 in the end of the tube 16 for sealing it. The end of the tube 16 is chamfered to form a seat for a shoulder 62 on the plug 61.

The plug 61 is preferably tapered from a point closely proximate to the rear side of the opening 57 to a point projecting beyond the opposite and inward side of the opening 57 so as to define a decreasing annular passage leading to the outlet opening 57. By this novel arrangement dripping even of the most viscous syrups is eliminated, for any liquid above the opening 57 tends to be drawn back onto the face of the taper and form on the plug 61 to drip or drain towards the point of the taper and fall back down the tube 16 instead of out the opening 57. The taper is easy to form and functions correctly regardless of any rotary changed position when in place.

In order to make the cap 60 easy to clean and to make sure that the plug 61 will not be left out and the cap alone used to seal the tube 16, an opening 63 through the end of the cap 60 is provided. Were it possible to use the cap 60 without the plug 61, not only would the pump be likely to drip, but a sharp corner which would be very hard to clean would result.

The pumps of this invention operate in the following manner each time the handle 27 on the preferred embodiment or the lever 52 on the modified embodiment is actuated:

Before the handle 27 is moved the various elements occupy the positions shown in Fig. 1. The piston 25 is at the top of the cup 22 adjacent to the plate 20, and the cup 22 is filled with syrup the valves 32 and 38 being closed. 75

As the handle 27 is moved downwardly against the force of the spring 44 the ball check valve 32 opens, as shown in Fig. 3, and syrup is forced up the tube 16 flowing out of the opening 57 and continuing to flow as the handle 27 is moved downwardly until motion of piston 25 is checked when the stop member 46 strikes the top of the sleeve 47. Thus, a measured quantity of syrup is delivered during the downward stroke of the piston 25.

When the pumping stroke has been completed and the pressure on the handle 27 is removed the spring 44 forces the piston 25 upwardly. As shown in Fig. 4, the valve 38 opens allowing syrup to flow into the cup 22 and the ball check valve 32 closes, preventing the back flow of syrup from the tube 16.

Attention is directed to the fact that there is present a novel relationship between the ball check valve 32 and the pointed plug 61 which cooperate to eliminate dripping. Because the ball 33 in the valve 32 is free to move a relatively long distance compared to the ball of a conventional check valve, the valve 32 does not close immediately when the piston 25 starts to move upwardly but permits a small quantity of syrup to be sucked back into the cup 22 causing a drop in the syrup level at the upper end of the tube 16. If this drop in level did not occur the pointed plug 61 would not be effective to prevent dripping for the syrup level would remain even with the opening 57 and drops would not form on the end of the plug 61 to fall to the surface of the syrup below the opening 57. Thus, the anti-drip feature of this pump is dependent on the operation of other parts of the pump remote from the discharge opening 57.

At the completion of the upward stroke of the piston 25, whose upper travel is limited by the plate 20, the cup 22 is filled with syrup and the valve 38 closes due to the action of gravity. In the event, however, that this valve should not close completely for some reason the initial downward movement of the piston 25 at the start 45 of the next stroke of the handle 28 causes the valve 38 to immediately seal positively against the bottom of the cup 22.

Throughout the foregoing description, mention has been made of the ease with which the various parts of the pump may be cleaned. However, for purposes of clarity a résumé of the cleaning procedure follows:

To clean the pump 10 the attendant first lifts it out of the jar 11 allowing the excess syrup to drain back into the jar and pushes up on valve 38 to release any syrup trapped in the pump either back into the jar or into another container so that it will not be wasted. Next, he grasps the cup 22 with his fingers and rotates it to release the bayonet lock 23 from the projections 21 on the plate 20 and moves the cup 22 downwardly away from the plate 20. The spring 44 expands to its full length permitting the piston 25 to drop to the fully depressed position as the cup 22 is moved away, and the spring 44 together with the valve 38 and the valve guide member 40 remain in the cup 22.

The attendant then lifts the spring 44 and the two parts of the valve 38 out of the cup for separate washing. Next, he withdraws the valve 32 from the end of the tube 16 and thoroughly cleans and washes the valve following the procedure set forth above in connection with the description of the valve. The cap 60 on the upper end of the tube 16 is then unscrewed and the

7
plug 61 is removed, the two being washed separately.

When the pump 10 has been disassembled to this stage the parts remaining assembled are completely exposed and may be thoroughly washed without difficulty, a brush being run into the tube 16 from each end to clean it and the piston 25 being moved back and forth so that the lower end of the outside of the tube 16 below the plate and the rod 26 can be cleaned. If desired, the handle assembly 19 may be disassembled simply by unscrewing the various parts from the shaft 26.

After all the parts have been cleaned they are reassembled and the pump is ready for reinstal- 15
lation on a clean syrup jar.

From the foregoing description it will be apparent that a novel and superior syrup pump has been developed. Various changes and modifications in the described embodiments such as will 20
present themselves to those familiar with the art may be made without departing from the spirit of this invention whose scope is com-
mensurate with the following claims.

What is claimed is:

1. A syrup pump comprising a cover plate adapted to be received on a syrup jar, a discharge tube passing through said cover plate to a point within the syrup jar, a second plate having a plurality of projections about its circumference disposed near the lower end of said tube, a cylindrical cup having a plurality of bayonet slots therein adapted to receive the projections of said second plate, an opening in each of said plates, a rod extending through both openings, a piston on the lower end of said rod having a diameter substantially the same as the inside of said cup, an opening through said piston through which the discharge tube passes, an inlet valve including a valve member and a valve guide spider disposed in the bottom of the cup, means for manually moving said rod downwardly to actuate said piston, and a coil spring received within said cup between said valve guide spider and the piston for moving said piston upwardly.

2. A syrup pump comprising a discharge tube, 45
a chamber at the lower end of said tube, means for exerting pressure on syrup in said chamber, a check valve assembly including a member received in the end of said tube, a movable ball disposed within said member, and a valve port in said member connecting the interior of said tube with said chamber, the member being of such length as to allow said ball to move at least twice the diameter of said tube away from said port, a discharge opening in the side of said tube near the opposite end thereof, and a removable pointed plug for closing the upper end of the tube, said plug extending downwardly to a point below the discharge opening so as to define a decreasing annular passage within the tube.

3. A syrup pump comprising a discharge tube, a chamber at the lower end of said tube, means for exerting pressure on syrup in said tube, a check valve assembly including a member removably received in the end of said tube, a movable ball disposed within said member, and a valve port in said member connecting the interior of said tube with said chamber, the member being of such length as to allow said ball to move at least twice the diameter of said tube up-
said tube away from said port, a discharge opening in the side of said tube near the opposite end thereof, and a removable plug for closing the upper end of said tube, the inner end of the plug being disposed below the discharge opening 75

8
whereby drippings from the plug as the liquid level in the tube is lowered fall back down the tube.

4. A syrup pump comprising a discharge tube, a chamber at the lower end of said tube, means for exerting pressure on syrup in said tube, a ball check valve removably received in the lower end of said tube, a discharge opening in the side of said tube near the opposite end thereof, a removable plug for closing the upper end of said tube, and a threaded cap having an opening through the end thereof for holding the plug in place.

5. A discharge conduit for a syrup pump comprising a unitary tube having two substantially straight portions connected by a relatively sharp curved portion the curvature being such that light is visible from either end of the tube when the other end is open and disposed adjacent to a source of light, a readily removable plug having a conical inner end and sealing the upper end of said tube, a discharge opening in the side wall of the tube near the plug said conical inner end extending inwardly beyond said discharge opening, and a check valve removably received in the opposite end of the tube, said valve comprising a member closing the end of the tube and having a valve port therein, a pair of prongs extending upwardly into said tube having inwardly bent ends, and a ball retained between said prongs said ball coacting with said port to seal same and prevent the back flow of liquid out of said tube.

6. A discharge conduit for a syrup pump comprising a unitary tube having two substantially straight portions connected by a relatively slightly curving portion, a removable plug having a conical inner end and sealing the upper end of said tube, a discharge opening in the side wall of the tube near the plug, said plug extending inwardly beyond said discharge opening, and a check valve removably received in the lower end of the tube.

7. A discharge conduit for a syrup pump comprising a unitary tube, a readily removable plug having a conical inner end and sealing the upper end of said tube, a discharge opening in the side wall of the tube near the plug, said plug extending inwardly beyond said discharge opening, and a check valve removably received in the lower end of the tube, said valve comprising a member closing the end of the tube and having a valve port therein, a pair of prongs on said member extending upwardly into said tube and having inwardly bent ends, and a ball retained between said prongs, said ball coacting with said port to seal same and prevent the back flow of liquid out of said tube, and outward pressure of said prongs against the conduit being the sole means of supporting the valve in the tube.

8. A syrup pump comprising a discharge tube, a plate attached to the lower end of said tube, a cylindrical cup removably attached to said plate, a piston disposed within said cup and movable from a position adjacent the plate to a point near the bottom of the cup, a check valve in the bottom of said cup permitting syrup to flow into the cup, a second check valve in the discharge tube closing in the direction of flow down said tube, a discharge opening at the upper end of said tube on the side thereof, and a removable plug for sealing the end of the discharge tube, the end of said plug being pointed and extending to a point below said discharge opening.

9. A syrup pump comprising a discharge tube,

a cylindrical cup disposed at the lower end of said tube, a piston within said cup and movable axially therein, an opening in said piston through which said tube extends, a check valve in the bottom of said cup permitting syrup to flow into the cup, a second check valve in the discharge tube closing in the direction of flow down said tube, a discharge opening at the upper end of said tube on the side thereof, and a removable plug for sealing the end of the discharge tube, the end of said plug being pointed and projecting to a point below said discharge opening.

10. In a device of the class described the combination including a discharge tube extending to a point below the normal liquid level; a circular plate having a plurality of projecting lugs spaced about its periphery and carried by said discharge tube, a cup having substantially the same diameter as said plate and a plurality of bayonet slots cooperating with said lugs to removably support said cup on said plate, an inlet valve port for permitting fluid to flow into said cup, a movably mounted piston in said cup for forcing fluid up the discharge tube out of said cup, and a spring disposed in said cup beneath the piston for maintaining an upward force on said piston and a downward force on said cup to hold said projections and said slots in engagement.

11. In a device of the class described the combination including a circular plate having a plurality of projecting lugs spaced about its periphery, a cup having substantially the same diameter as said plate and a plurality of bayonet slots cooperating with said lugs to removably support said cup on said plate, an inlet valve port for permitting fluid to flow into said cup, a movably mounted piston in said cup for forcing fluid up out of said cup, and a coil spring in said cup for urging said piston upwardly, the compressive force of said spring urging said cup downwardly to maintain tight engagement of the lugs and the bayonet slots.

12. In a syrup pump the combination including a discharge tube extending to a point within a syrup jar, a plate having a plurality of projections about its circumference disposed near the lower end of said tube, a cylindrical cup having a plurality of bayonet slots therein adapted to receive the projections of said plate, a piston having a diameter substantially the same as the inside of said cup and an opening therein through which the discharge tube extends, an inlet valve including a valve member and a valve guide spider disposed in the bottom of the cup, means for moving said piston downwardly, and a coil spring received within said cup between said valve guide spider and the piston for moving said piston upwardly, said spring also serving to maintain tight engagement of the projections in said slots.

13. A syrup pump comprising a discharge tube extending to a point within a syrup jar, a plate having an opening therethrough and a plurality of projections about its circumference, said plate being disposed near the lower end of said tube, a cylindrical cup having a plurality of bayonet slots therein adapted to receive the projections of said plate, a manually moveable rod extending through the opening in said plate, a piston on the lower end of said rod having a diameter substantially the same as the inside of said cup and an opening through said piston through which the discharge tube passes, an inlet valve at the bottom of said cup including a valve member and

a removable valve guide and a coil spring received within said cup beneath said piston for urging said piston upwardly and maintaining a downward tension on said cup to hold the bayonet joint in engagement.

14. In combination with a pump for dispensing soda fountain syrup and the like from a generally upright open-topped syrup container, a delivery spout receiving syrup from said container by means of said pump, said delivery spout extending over a side of said container and having at least its outer end portion sloping downwardly when said container and pump are in their normal dispensing positions, the outer end portion of said delivery spout having an outlet orifice in the underside thereof at a spaced distance from said outer end of said spout, and a closure for the end of said spout blocking said spout above said orifice, said closure providing an internal extension of smaller diameter than the internal diameter of said spout, spaced from the walls of said spout and extending downwardly therein over said orifice to a point below said orifice, whereby upon the lowering of the level of syrup in said spout to a point below said orifice immediately after discharging the syrup through said orifice, any portions of syrup remaining above and around said orifice are induced to rundown said extension to a point below said orifice rather than through said orifice so that said orifice is prevented from dripping.

15. In combination with a pump for dispensing soda fountain syrup and the like, said pump including a measuring cylinder equipped with inlet and outlet ports and adapted to be suspended within a syrup container, an outlet tube communicating with said cylinder outlet port and extending upwardly to a point above and outboard of said container, the outer end portion of said outlet tube being aligned to slope downwardly when said pump is in its normal dispensing position within said container and having an outlet orifice in the underside thereof at a spaced distance from said outer end of said tube, a plug adapted to close the end of said tube and to block said tube above said orifice, said plug having an internal extension of considerably smaller diameter than the internal diameter of said tube extending downwardly within said tube over said orifice to a point below said orifice, whereby upon the withdrawal of the level of syrup within said outlet pipe to a point below said orifice, after the completion of a dispensing stroke of said pump, any portions of syrup remaining above and around said orifice are induced to run down said extension to a point below said orifice rather than through said orifice so that said orifice is prevented from dripping.

16. A syrup pump comprising a support adapted to be mounted on a syrup receptacle, a discharge tube carried by said support, a hollow cup at the lower end of the discharge tube, a moveable piston within said cup, a rod extending from the piston to a point above the support, a head mounted on the end of the rod, stop means threadably supported on the rod below said head and adjustable axially thereof including two abutting elements, one of which telescopes with said support in guided relationship, and the other one of which mates with said head, an element on said support cooperating with said other element, and means for moving said rod downwardly including a lever having a handle thereon engaging said head.

17. In a syrup pump, the combination comprising a cover plate adapted to be received on a syrup

11

jar, a discharge tube carried by said cover plate, a second plate disposed near the lower end of said tube, an opening in each of said plates, a rod extending through both said openings, a piston on the lower end of said rod sliding upon said discharge tube and supported thereby against rotation, a cylindrical cup supported beneath said second plate having an internal diameter substantially the same as the piston, a head secured on the upper end of the rod, and means axially 10 adjustable to various positions with respect to the rod for limiting travel of said piston including a stop member and a locking member threadably supported on the said rod below the head to cooperate with each other, one of said members telescoping with the cover plate in guided relationship, and the other of said members telescoping with said head when moveable independently thereof to jam lock said one member, an element upon one of said members cooperating with said 15 cover plate to limit the downward movement of the rod.

18. A syrup pump comprising a support adapted to be mounted on a syrup receptacle, a discharge tube carried by said support and extending above and below the same, a circular plate near the lower end of the discharge tube, a hollow cup marginally engaging said plate, said plate and cup being so constructed and arranged at their engagement that the plate is attached to said cup with a releasable bayonet joint engagement, a moveable piston within said cup, a valve member in the bottom of the cup, a removable guide for supporting and limiting upward movement of said valve member, a spring disposed beneath said piston and above said guide in said cup to urge maintenance of said bayonet joint engagement, and means including a handle and a rod extending downwardly through an opening in said plate to the piston for manually 20 moving said piston downwardly in said cup, said movement being in the direction of compressing said spring.

12

19. A syrup pump comprising a discharge tube extending to a point within a syrup jar, a plate disposed near the lower end of said tube, a cylindrical cup supported below said plate, a manually moveable rod extending through the opening in said plate, a piston on the lower end of said rod having a diameter substantially the same as the inside of said cup and having an opening through which the discharge tube passes, an inlet valve at the bottom of said cup including a moveable valve member and a removable valve guide resting against the bottom of the cup for retaining said valve member against excessive upward movement, and a coil spring received within said cup under compression between said piston and valve guide, one end of the spring engaging said piston for urging said piston to its uppermost retracted position and the other end of the spring engaging the top of the valve guide for maintaining a downward force on said valve guide and cylindrical cup.
